UNITED STATES PATENT OFFICE.

EMMA C. STEEN, OF WAHOO, NEBRASKA.

CARPET-TACK.

SPECIFICATION forming part of Letters Patent No. 623,847, dated April 25, 1899.

Application filed December 17, 1896. Serial No. 616,078. (No model.)

To all whom it may concern:

Be it known that I, EMMA C. STEEN, a citizen of the United States, residing at Wahoo, in the county of Saunders and State of Nebraska, have invented certain new and useful Improvements in Carpet-Tacks; and I do hereby declare the following to be a full, clear, and exact description of the invention, such as will enable others skilled in the art to which it appertains to make and use the same.

My invention relates to carpet-fasteners; and the object thereof is to provide simple and effective securing devices adapted to remain permanently in the floor. A considerable part of the labor incident to laying, stretching, and securing carpet in the old way with ordinary tacks is obviated, as the fasteners have permanent place, it being only necessary to hook the carpet thereto at one edge, and then, after laying, smoothly engage the other edges with the previously-placed fasteners. When the carpet is to be taken up, it is simply unhooked from the fasteners, leaving the latter in place for the next laying. A great saving in tacks is effected and the inconvenience of extracting same is avoided.

The invention consists in the novel features of construction hereinafter fully described and claimed and illustrated by the accompanying drawings, in which—

Figure 1 is a perspective view illustrating a section of carpet secured by my improved fastener. Fig. 2 is a cross-section of the fastener-shank. Fig. 3 is a detail view of the fastener provided with a spacing-collar. Fig. 4 is a similar view showing the fastener provided with a spacing-collar and hook-closing latch for locking the carpet.

The fastener consists of a pointed shank 1, preferably square in cross-section, and at its upper end provided with the right-angled spear-shaped head 2, which tapers gradually and terminates in a sharp point. The under surface of the head, except as hereinafter indicated, is flat, making flat engagement or bearing on the carpet and holding the same flatly on the floor without tendency to spring up and become disengaged. The elongated gradually-tapered and acutely-sharpened head readily penetrates the carpet and passes the incision therein to the fastener-shank without rupturing the warp and weft of the

carpet. This is a marked advantageous feature of superiority over hook-fasteners heretofore proposed having blunt hooks and points which of necessity tear the carpet when passed therethrough, and a tear thus started will increase under subsequent strain. With the carpet absolutely sound after being placed on my approved fasteners it has much greater strength to withstand hard wear, and danger of tearing from the fasteners is proportionately reduced.

The flat under face of spear-head 2 is formed with beard 3, Figs. 3 and 4, to prevent accidental disengagement of the carpet, and if greater security is desired spring locking-tongue 5 may be provided, which bears against the shoulder of beard 3 in snap-hook fashion. The fastener-shanks may be provided with collars 4 for uniformly spacing heads 2 from the floor, and when employed in conjunction with spring-tongues 5 may carry the latter, as in Fig. 4, though the collar and tongue may be used each without the other without departing from my invention.

Having thus described the invention, what is claimed as new, and desired to be secured by Letters Patent, is—

1. An improved carpet-fastener consisting of a pointed shank adapted to enter the floor, a pointed head projecting laterally from the shank, the head being of gradually-increasing thickness from the point toward the shank, the under side of the thickened portion terminating abruptly to form a shoulder which parallels the shank, thus constituting a barb or beard which automatically holds the carpet from disengagement, substantially as shown and described.

2. A fastener of the class described, comprising a shank provided with a horizontal head extending at right angles thereto, a beard formed on the free end of said head, and a collar formed on the shank intermediate the ends thereof but spaced from the horizontal head, substantially as set forth.

3. A fastener of the class described, comprising a shank, a head formed on said shank, and a spring-tongue also carried by the shank and adapted to engage said head to lock the carpet or other material on the shank, substantially as set forth.

4. A fastener of the class described, com-

prising a shank, a head formed on said shank and provided with a beard, and a spring-tongue carried by said shank and adapted to engage with said beard to lock the carpet on the shank, substantially as set forth.

5. A fastener of the class described, comprising a shank, a head formed on said shank and provided with a beard, a collar also formed on said shank and adapted to limit the movement of the latter when forced into the surface upon which the carpet or other material is placed, and a spring-tongue formed on said

collar and adapted to engage with the beard of the head to lock the carpet on the fastener when said carpet is passed over said head, substantially as set forth.

In testimony whereof I have signed this specification in the presence of two subscribing witnesses.

EMMA C. STEEN.
